UNITED STATES PATENT OFFICE.

JOHN RAPHAEL ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,088,729.

Specification of Letters Patent.

Patented Mar. 3, 1914.

Application filed July 25, 1911. Serial No. 640,470.

To all whom it may concern:

Be it known that I, JOHN RAPHAEL ROGERS, a citizen of the United States, and a resident of Brooklyn, county of Kings, and State of New York, have invented a new and useful Improvement in Typographical Machines, of which the following is a specification.

My invention relates to typographical machines and more particularly to the class thereof known to the public under the name "linotype" and as represented for instance in U. S. Letters Patent to O. Mergenthaler, No. 436,532. In such a machine, the matrices are assembled in line and presented to a mold, wherein the slug or linotype is cast, after which they are returned to the appropriate channels in the magazine by a distributing mechanism, which comprises a longitudinally grooved bar or rail, along which they are advanced by rotating screws in the manner well understood in the art, and as particularly illustrated in U. S. Letters Patent to O. Mergenthaler, No. 347,629.

My invention more particularly relates to such a distributing mechanism, and even more specifically to that type thereof illustrated in U. S. Letters Patent to D. S. Kennedy, No. 890,283, dated June 9, 1908. In the said Kennedy patent are illustrated and described devices wherein the matrices are first separated as to fonts, after which they are delivered to the regular distributing mechanism, by which they are conveyed to their respective magazines; and in the present instance, I have shown my improvements as applied to such a font distributor or separator, although obviously they are similarly applicable to the ordinary magazine distributor, or in fact to any form of distributing apparatus. Furthermore, many changes and modifications may be made therein without departing from the spirit of my invention, and generally speaking, I do not limit myself to any specific form or embodiment except in so far as such limitations are specified in the claims.

It sometimes occurs, in the ordinary operation of the distributing devices, that a matrix becomes jammed or misplaced without being disengaged from the conveying screw, or that even if freed from the screw, it is so lodged as to prove an obstacle to other matrices which are being advanced in the regular manner. In either instance, unless the

rotation of the screw be checked, there is great danger of the breakage, bending or other disarrangement of the parts, and I therefore herein show means to check this rotation in such circumstances, and thus to avoid the evil results previously mentioned.

In the accompanying drawing: Figure 1 is a front view of a portion of the distributing devices of a linotype machine, partly broken away; and Fig. 2 is a perspective view of certain of the parts, on an enlarged scale.

Referring to the drawings, the font distributing or separating devices A are or may be of the general character disclosed in the beforementioned Letters Patent to Kennedy, to which reference may be had for details not herein specifically mentioned. The equivalent mechanism herein comprises the block A¹, formed with guiding surfaces A² and alternating depressions A³, and the bridges or selectors L mounted upon their supports K, which supports are connected to the block A¹. Similarly, there is a distributor rail or bar, not herein shown, and three conveying screws rotating in proximity thereto, two of which only, D and E, are herein illustrated. The conveying screws D and E are rotated by pinions D¹ and E¹ respectively connected thereto, the said pinions meshing into and being actuated by a driving pinion G¹. Also connected to the screw D is the pinion D² which imparts rotation to the third distributor screw, not herein shown.

The screw E is located within the cylindrical bore A¹⁰ formed in the block A¹, and the block is connected to or integral with the laterally projecting piece A²⁰. It will be seen that due to the rigid connections between the block A¹, piece A²⁰, supports K and bridges or selectors L mounted thereon, the said parts may be regarded as constituting one rigid entity, the whole being mounted in suitable guides so as to be capable of a slight longitudinal movement, as indicated by dotted lines in Fig. 2. This longitudinal movement of the block A¹ and connected parts is independent of and relative to the conveying screws, which latter are mounted in the stationary frame.

Motion is imparted to the distributing mechanism by the belt M and pulley M¹ mounted on the shaft M⁴. A sprocket chain and gearing M² transmits motion

from the shaft M^4 to the gearing M^3 , which effects the rotation of the ordinary distributer screws, as well known in the art. These latter connections and gearing, however, in themselves, do not constitute a part of my present invention and further description thereof will therefore be unnecessary. Also suitably connected to the shaft M^4 is a driving pinion N , which meshes into a pinion N^1 on the shaft O , which with its connected parts is suitably journaled in the main frame, as in the bearings O^2 . The shaft O imparts motion to the distributer screws, and to that end is provided with a clutch member O^1 fast thereon, adapted and arranged to mesh into and actuate the sleeve P , which is loosely mounted upon the shaft O and so as to be capable of a sufficient longitudinal movement with relation thereto as to permit its engagement with and disengagement from the clutch member O^1 . The previously mentioned driving pinion G^1 is mounted on the end of the sleeve P , and it is to be noted that this pinion is so constructed and located as to permit of the longitudinal movement of the sleeve without disengaging the pinion from the pinions D^1 and E^1 meshing therewith.

In the normal operation of the parts, the sleeve P engages with the clutch member O^1 (see Fig. 2) so as to cause the rotation of the sleeve and the gearing connected thereto, and consequently also of the conveying screws. When, however, the engagement of the sleeve and clutch member is broken (see Fig. 1) the rotation of the sleeve, gearing and conveying screws is arrested.

Formed upon the sleeve P is a circumferential groove P^2 , which engages with a pin Q^2 carried by the lever Q pivoted at Q^1 to the main frame. A spring Q^3 , connected to one arm of the lever Q and to the bearing O^2 , normally tends to break the connection between the sleeve P and clutch member O^1 . This tendency of the spring Q^3 is however resisted and controlled by the pin Q^4 carried by the other arm of the lever Q , and which rests upon and is sustained by the pin A^{30} carried by the piece A^{20} , this being the normal condition of the parts as shown in full lines in Fig. 2.

When a matrix becomes jammed or is otherwise improperly placed but is still engaged by one of the screws, or even if disengaged becomes an obstacle in the path of the other matrices which are being advanced in the regular way, the block A^1 and piece A^{20} are longitudinally displaced thereby, and because of this the pin A^{30} is caused to pass from under and to disengage the pin Q^4 . This permits the spring Q^3 to move the sleeve P longitudinally, and thus to break its operative connection to the clutch member O^1 on the shaft O , thereby checking the

rotation of the conveying screws. In Fig. 2, for example, a matrix X is shown as wedged between one of the bridges or selectors L and the thread of the rotating screw E . As the screw continues its rotation, the block A^1 is moved from the full line to the dotted line position, thus releasing the lever Q and permitting the spring Q^3 to break the operative connection between the parts as previously set forth. In other words, I avail myself of the shifting from normal position of one of the distributer elements to actuate the clutch releasing mechanism and thereby to arrest the rotation of the conveying screws, before injury to the parts is caused. Further, the normal tendency of the spring Q^3 to open the clutch effects the instantaneous arrest of the distributing mechanism as soon as the spring is permitted to operate, thus making the stop mechanism more responsive and avoiding the appreciable period of time that elapses in other forms, wherein even after the tripping of the parts, the disconnection is not actually effected until a further rotation of the operating means permits it. In other words, I provide devices for opening the clutch independently of the operation of the actuating means immediately upon the abnormal operation of the distributing mechanism.

Having thus described my invention, its construction and mode of operation, what I claim and desire to secure by Letters Patent of the United States is as follows:

1. In a typographical machine, the combination of distributing devices comprising a movable part, operating mechanism for said devices, and means tending constantly to disconnect it from the distributing devices, independently of its operation, the said means being controlled by the movable part.

2. In a typographical machine, the combination of distributing devices comprising a movable part, operating mechanism for said devices, means tending constantly to disconnect it from the distributing devices independently of its operation, and connections from said movable part whereby the disconnecting means are resisted or unresisted according to the position of the movable part.

3. In a typographical machine, the combination of distributing devices comprising a movable part, operating mechanism for said devices, and a spring acting directly to disconnect the operating mechanism from the distributing devices, the spring being controlled in its action by the movable part.

4. In a typographical machine, the combination of distributing devices comprising the movable part A^1 , operating mechanism for said devices comprising a clutch, the spring Q^3 acting directly to disengage said

- clutch, and connections to maintain the engagement of said clutch in opposition to the spring, the said connections adapted to be tripped by the movement of the part A¹.
5. In a typographical machine, the combination of distributing mechanism comprising the movable part A¹, operating mechanism for said devices comprising the driving member O¹ and the driven member P, the spring Q³ for disengaging said members, and the pivoted lever Q for effecting the engagement of said members in opposition to the spring, the said lever adapted to be tripped by the movement of the said part.
10. P, the spring Q³ for disengaging said members, and the pivoted lever Q for effecting the engagement of said members in opposition to the spring, the said lever adapted to be tripped by the movement of the said part.
15. In a typographical machine, the combination of distributing mechanism, actuating means therefor comprising a clutch, and devices for opening the clutch independently of the operation of the actuating means, the said devices being permitted to act upon the abnormal operation of the distributing mechanism.
20. In a typographical machine, the combination of distributing mechanism, actuating means therefor, comprising a clutch, a spring to open the clutch directly, and means for closing the clutch in opposition to the spring, the said means adapted to be tripped upon the abnormal operation of the distributing mechanism.
25. In a typographical machine, the combination of distributing mechanism, actuating means therefor, comprising a clutch, a spring to open the clutch directly, and means for closing the clutch in opposition to the spring, the said means adapted to be tripped upon the abnormal operation of the distributing mechanism.
30. In a typographical machine, the combination of distributing mechanism, actuating devices connected thereto, and means tending constantly to disconnect them directly, the said means being rendered effective upon the abnormal operation of the distributing mechanism.
35. In a typographical machine, the combination of distributing mechanism, actuating means therefor comprising a clutch, and a spring for opening the clutch directly, the said spring being permitted to act upon the abnormal operation of the distributing mechanism.
40. In a typographical machine, the combination of distributing mechanism, actuating means therefor comprising a clutch, a spring to open the clutch directly, and means for holding said spring out of action when the clutch is closed, the said means adapted to be tripped upon the abnormal operation of the distributing mechanism.
45. In a typographical machine, the combination of distributing mechanism, actuating means therefor comprising a clutch, a spring to open the clutch directly, means for closing the clutch in opposition to the spring, and devices for tripping said means upon the abnormal operation of the distributing mechanism.
50. In testimony whereof I hereunto set my hand this 24th day of July, 1911, in the presence of two attesting witnesses.
